UNITED STATES PATENT OFFICE.

RICHARD SMITH, OF BOSTON, MASSACHUSETTS.

MECHANISM FOR ACTUATING GUIDE-ROLLS.

SPECIFICATION forming part of Letters Patent No. 395,253, dated December 25, 1888.

Application filed May 7, 1887. Serial No. 237,410. (No model.)

To all whom it may concern:

Be it known that I, RICHARD SMITH, a citizen of the Dominion of Canada, residing at Boston, in the county of Suffolk and State of Massachusetts, have invented certain new and useful Improvements in Mechanism for Actuating Guide-Rolls; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to mechanism for automatically actuating guide-rolls, by means of which the direction in the travel of an endless apron—such as drier or wet felts or a wire-cloth—may be controlled, such movements of the guide-rolls being caused by the edges of the apron and due to the divergence of the latter from its normal path of travel.

This invention is an improvement on that described in Letters Patent of the United States No. 339,703, issued to myself on the 13th day of April, 1886. In that invention the guide-roll was mounted upon a sliding carriage, which was thrust endwise in either direction by the operation of two pawls hung upon a rocking shield, and which engaged a toothed gear. This latter gear rotated a pinion which meshed with a fixed rack upon the machine-frame, while the rocking movement of the shield was caused by a face-plate upon one end of the roll, the position of which was shifted and altered by the pressure of the edge of the endless apron against feather-bars. Interconnecting mechanism from the latter tilted the shield, and thus brought one of the pawls into active service, dependent upon the direction in which the thrust from the apron was exerted. In that construction it will be readily understood that both pawls are inactive only when the rocking shield is horizontal and not tilted one way or the other; but as this occurred only at the time when the endless apron was traveling directly at right angles to the longitudinal axis of the guide-roll, which interval in practice seldom occurs, it was found that the felt or endless apron was being actuated unnecessarily by the operating mechanism.

The object of my present invention is to overcome these objections and render the actuating-pawls intermittently active. To effect this result, in lieu of being permitted to advance the carriage on which the journal of the guide-roll is mounted as long as the pressure of the endless apron continues in one direction, said pawls are allowed to act only for a short interval, to produce a certain small change in the position of the roll, and are then rendered inactive. Thus the felt or wire cloth is given an opportunity to feel the change by the shifting of the roll, when if said shift is sufficient no further advance is made in this direction; but should this change not suffice and the pressure from the traveling apron be continued, said pawl is again rendered active and a further slight alteration is effected, when the pawl again becomes inactive.

The drawings accompanying this specification represent, in Figure 1, a side elevation. Fig. 2 is a plan; Fig. 3, an end elevation of devices for automatically actuating guide-rolls, and which embodies my invention. Fig. 4 is a transverse sectional elevation through plate I. Fig. 5 is a general plan of the mechanism as applied in connection with the felt of a paper-making machine. Fig. 6 represents a perspective view of the mechanism as a whole. Fig. 7 represents a detail elevation of the rear feather-bar and the pivotal mounting of bar h.

In said drawings I have represented at A a housing or standard to be rigidly affixed or bolted to one side (the front) of the frame of a paper-machine. (Not shown.) This standard is T-shaped in general cross-section in a plane parallel to shaft d, and is composed of a vertical web, B, and two lateral ones, C D, which are disposed parallel with the side of the machine-frame. The top surface of the piece C is surmounted by a rack, S, toothed at a a, with which two oppositely-disposed gravity-pawls, E F, engage at certain desired intervals. These pawls are loosely hung upon a stud, b, located eccentrically in the face-plate c, rigidly secured upon the end of the rotating journal d of the guide-roll G. This roll, over which the endless apron shown by the broken line 2 travels, and by means of which its path of movement is controlled, has one of its journals mounted in a bearing piv-

oted to a fixed part of the frame, while the other journal, *d*, is mounted in the carriage *H*, the latter being provided with an undercut groove, *l*, to grasp the upper and under faces 5 of the web *D* before mentioned, upon which it is free to move endwise in the act of shifting the position of the roll to operate the endless apron or felt.

To prevent continuous action of the pawls 10 with respect to the toothed rack *S*, I have erected midway between the webs *C* *D* and parallel therewith a guide-plate, *I*, slotted at *P*, Fig. 4. A "shield," *J*, so called since it covers the teeth *a a* of the rack, is mounted 15 on rollers *f f*, which travel in said slot when the lateral thrust upon the feather-bars is transmitted thereto. This thrust is caused by the pressure of the wire, cloth, or felt. A rod, *h*, extends transversely across the ma- 20 chine and is further provided with the feather-bars *g g*. (See Fig. 5.) One end of this rod is pivoted, as shown in the patent above alluded to, while the other end is secured to a bell-lever, *i*, pivoted upon the frame *D*, and 25 united by the rod *j*, pivotally attached at *k* to the shield. The rod *j* is also pivotally attached to said bell-lever *i*. Reciprocations of the said rod thus cause the shield *J* to slide, and the latter permits one of the pawls, by 30 withdrawing from beneath it, to drop upon the rack *S* and engage its teeth *a*. The continuous rotation of the guide-roll *G* actively thrusts the carriage *H* endwise by means of the now active pawl. When the latter has 35 advanced itself into contact with the shield, it is lifted up by the said shield and rendered inactive, while the carriage *H* is stopped.

The operation of the above mechanism is as follows: Presuming the parts are as shown in 40 the drawings with the guide-roll rotating as indicated by arrow 1, (see Fig. 1,) the felt is also diverging, as shown by arrow 3, Fig. 2. In such event the pressure of the felt or wire cloth is against one of the feather-bars *g*, 45 while the rod *h* will be thrust in the direction of arrow 4. The effect of this will be, by aid of the bell-lever *i* and rod *j*, to move the sliding shield *J* in direction of arrow 5 and to withdraw it from beneath the pawl *F*, which 50 then drops into contact with the teeth *a* of the rack *S*. Since the latter is a fixture the carriage *H* is forced to move in the same direction as the shield, while the axis of the guide-roll is canted to shift the felt and cause 55 it to diverge in a contrary direction. The guide-roll can now make but a few revolutions before the pawl *F* has thrust the carriage *H* to such a position that the pawl is in contact with and rests upon the shield, and 60 all the parts now remain inactive until further divergence of the felt in the direction of arrow 5 has again advanced the shield to permit activity of the pawl to cant the guide-roll still more. This intermittent action is 65 repeated successively until the divergence of the felt one way is counteracted by the obliquity in the axis of the roll oppositely. The

advantages of this intermittent feed motion will be seen from the fact that after the roll is shifted a pause or interval ensues to allow 70 the felt to be influenced before any further change in the same direction is effected. Moreover, the parts are not in constant action and there is less opportunity for wear and consequent deterioration. To prevent ac- 75 cidental movement of the guide-roll after being shifted, and so maintain its adjusted position, I have disposed on the lower part of the carriage a friction-clamp, *p*, adjustable by means of the screen *s*. By these 80 means all movements of the carriage and guide-roll are prevented except such as are produced by the action of one or the other of the pawls, and this resistance to accidental movements is effected without increasing the 85 strain or work upon the belt or apron, since the latter is simply required to slide the shield *J*, which is mounted on the rollers *f f*, and offers but little resistance to the movements of the said apron. A resistance occasioned by 90 the clamp *p* is sustained and overcome by the pawls and the actuating guide-roll.

I claim—

1. The combination of a fixed rack, a carriage movable longitudinally thereof, a guide-roll having one of its journals mounted in said carriage, a pivoted bearing for the other journal of said roll, and an endless apron traveling over said roll, with two pawls reversely inclined and carried by the former journal of 100 said roll, a movable shield which normally holds said pawls out of engagement with said rack, and devices connecting with said shield and extending to the edge of the apron in order that any lateral motion of said apron may 105 move them and cause them to move the shield from below one of the pawls, for the purpose set forth.

2. A guide-roll, a pivoted bearing for one of its journals, a carriage in which the other journal is mounted, devices for actuating said carriage, a fixed web, and a friction-brake attached to said carriage and bearing against said web to prevent accidental motion of said carriage, substantially as set forth.

3. The combination of guide-roll *G*, a pivoted bearing for one journal thereof, a carriage in which the other journal is mounted, two opposite inclined pawls carried by the latter journal, a fixed rack under said pawls, 120 a movable shield which normally holds said pawls out of engagement, the endless apron traveling over said roll, the feather-bars operated by the lateral motion of said apron, the rod *h*, and bell-lever *i f*, whereby said motion of the apron causes said shield to move from under one of the pawls, substantially as set forth.

4. The combination of a fixed rack, a shield which covers it, a traveling apron, and a roll 130 over which said apron passes, with a series of devices between said shield and the edge of said apron, whereby the lateral movement of said apron causes shield to move longitudi-

nally of said rack, a pivoted bearing for one journal of said roll, and a carriage for the other journal of said roll, a pair of inversely-inclined pawls carried by the latter journal and arranged above said shield in order that one of said pawls may drop into engagement with the rack when the shield moves toward the other pawl and be lifted again when the

carriage overtakes said shield, substantially as set forth.

In testimony whereof I affix my signature in presence of two witnesses.
